UNITED STATES PATENT OFFICE.

WILLIAM K. CRAPNELL, OF JOY, ILLINOIS.

DEVICE FOR DIPPING STOCK.

No. 888,001.

Specification of Letters Patent.

Patented May 19, 1908.

Application filed July 1, 1907. Serial No. 381,811.

To all whom it may concern:

Be it known that I, WILLIAM K. CRAPNELL, citizen of the United States, residing at Joy, in the county of Mercer and State of Illinois, have invented certain new and useful Improvements in Devices for Dipping Stocks; and I do hereby declare that the following is a full, clear, and exact description of the invention, which will enable others skilled in the art to which it appertains to make and use the same.

My invention relates to a device for use in dipping stock.

The object of the invention is to provide a simple and convenient arrangement whereby hogs and cattle and other stock may be driven into it and precipitated therefrom into the usual dipping tank used for such purposes.

It is well known that farmers and even dealers in stock very often find it necessary to treat the stock to a disinfecting solution for destroying disease germs and the like, and so far as my knowledge goes it has been customary heretofore to dip the stock by driving them up a "run" and then pushing them into the tank containing the solution. As this work is very laborious and unsatisfactory I have devised a device by which very little work is necessary and by which, also, a great many animals can be treated in much less time than heretofore.

In the appended drawings Figure 1 is a side elevation of my device surmounting a dipping tank. Fig. 2 is an end view of the same. Fig. 3 is a perspective view of a portion of the device. Fig. 4 is a view of the bottom. Fig. 5 is a perspective view of a portion of the device. Fig. 6 is a side view 40 of those parts shown in Fig. 5.

A represents a tank for containing the dipping solution, above which is mounted an enclosure having two sides and an end represented by B and C, respectively, the other end being open as shown in Fig. 3 at which terminates a run-way shown in Fig. 1 at D and which, though not so shown, may connect with the stock pen. The bottom of the enclosure consists preferably of two doors E E adapted to open downward as indicated in broken lines in Fig. 2 and as shown clearly in Fig. 3. These doors are hinged at F to the lower members of the sides B as in Fig. 5 wherein one-half of the hinge of one of the 55 doors is secured on the top of one of said members, while the other portion of said

hinge is attached to the door substantially in the position shown. One of the doors has a cleat G secured thereto near each end as shown in Fig. 4 one end projecting beyond the free edge of the door and extends beneath the other door, the purpose of which will be described presently.

Secured on one of the lower side members are two brackets H to one of which is pivoted a hand lever J, the other having pivoted thereto a short lever K, the upper end of the latter having connection with the said lever J by means of a rod L. The lower ends of both levers are bent at right angles and extend inward within notches M in the said bottom member as clearly shown in Fig. 5, said bent ends adapted to extend slightly beneath one of the doors so as to support the free ends of the cleats G already described. At 75 one end of the inclosure is a rock-shaft N having suitable bearings upon the lower members of the sides B, and one end of said shaft has an upturned arm O connected to the lever J by means of a rod or link P. Said shaft 80 also has extending inwardly therefrom near each end a projection or pin Q as shown in Fig. 4. However, when the stock within the tank is entirely cleared from the vicinity of the doors, the lever during its movement toward its normal position for supporting said doors will rock the shaft N and the latter will carry the pins Q downward past the line of the hinges thus freeing the doors and allowing the springs, which are under tension, to 85 at once raise and close the doors so that the arms G attain the proper position to be engaged by the levers. It is to be understood that the action just described takes place the moment the pins are moved slightly below 90 the hinge line so that the doors are in place before the bent end of the levers reach the position for supporting them. Fig. 1 shows the extreme lower position of the pin Q when the lever J is in the position shown in full 100 lines but as just intimated merely a slight movement of the pins in a downward direction is sufficient to release the doors since the axis of the shaft carrying them is substantially at the same height as the pivots of the 105 hinges. The operator can, of course, move the lever only partially to release the doors and then complete the movement thereof after the latter are at rest. The springs of the door shown at the right of Fig. 2 *i. e.* the door 110 that is supported by the projecting ends of the arms G, is normally under greater tension

than the opposite one whereby its doors will close before the door having the said arms G can rise to position. This insures the proper relative position of the parts during and after the closing movement. One of the sides B, as shown in Fig. 2, is provided with a door B', having a suitable fastening at B² which door provides for allowing the operator to reach the interior of the inclosure and the tank when necessary for any purpose.

I do not confine myself to the particular manner in which the doors are supported since any other means may be used for that purpose and I may use but one lever instead of two for supporting the doors. Furthermore, I may use other means by which to hold the doors in an open position and may also use means other than the springs for the closing operation.

Having thus described my invention, I claim:

1. A device for dipping stock comprising an inclosure, a bottom therefor adapted to open downward by weight thereon, coacting means for supporting the bottom and manually operated to release the same, and means for returning the bottom to its normal closed position.

2. In a device for dipping stock, an inclosure, a bottom therefor adapted to open downward by weight of the stock thereon, means for automatically raising the bottom to its normal closed position, and means for supporting the bottom in a closed position and manually operated means by which to release the same.

3. In a device for dipping stock, an inclosure, a bottom therefor adapted to open downward by weight of the stock thereon, means in connection with the bottom and placed under tension by the opening movement thereof for positively raising and closing said bottom, means for positively holding the bottom in the open position, and other coacting means for positively supporting the bottom when raised and closed.

4. In a device for dipping stock, an inclosure, a bottom for the same adapted to open downward by weight imposed thereon, coacting means for supporting the bottom in its closed position and manually operated to permit said bottom to open, and means operated by the first described means for holding the bottom in its open position, and means for returning the bottom to its closed position.

5. In a device for dipping stock, an inclosure for the stock, a fluid tank beneath the inclosure, a bottom for substantially the entire inclosure, said bottom adapted to open downward to precipitate the stock into the tank, means for supporting the bottom in its closed position, means for supporting the first said means and manually operated to release the same substantially as described.

6. In a device for dipping stock, an inclosure for the stock, a fluid tank beneath the inclosure, a two part bottom for substantially the entire inclosure, said bottom adapted to open downward to precipitate the stock into the tank, means for supporting both parts of the bottom in their closed positions, means for holding the first said means and manually operated to release the same substantially as and for the purposes described. 75

7. In a device for dipping stock, an inclosure for the stock, a fluid tank beneath the inclosure, a bottom for substantially the full area of the inclosure, said bottom adapted to open downward to precipitate the stock into the tank, coacting means for supporting the bottom, means whereby the bottom may be released, means whereby said bottom may be held open, and means for automatically raising and closing said bottom. 80

8. In a device for dipping stock, an inclosure, a bottom comprising two doors adapted to open downward away from one another by weight imposed thereon, means in connection therewith for supporting them, manually operated means for liberating said doors, and means for returning the doors to their normal closed positions. 85

9. In a device for dipping stock, an inclosure for receiving the stock, a bottom comprising two doors hinged to open downward away from each other by weight of the stock thereon, means for supporting the doors in their normal closed positions, manually operated means by which to release the doors 95 means acting automatically in connection therewith for holding the doors in their open positions, and means for automatically closing the doors. 100

10. In a device for dipping stock, an inclosure for receiving the stock, a collapsible bottom comprising two doors adapted to open downward away from one another, cleats attached to one of them and extending beneath the other, a bent lever for engaging and holding the cleats and supporting the doors, means in connection with the lever for locking the doors in the open position, and springs for closing the doors. 105 110

11. In a device for dipping stock, an inclosure for the stock, a fluid tank beneath the inclosure, a bottom of two sections for substantially the full area of the containing space of said inclosure, means secured to one of the bottom sections and extending beneath the other section and arranged to support both of them, manually operated devices adapted to at will engage the first said means to support the sections, springs for raising the section to the closed position, and means operated by one of the said devices for holding the doors open against the closing action of the said springs. 115 120 125

12. In a device for dipping stock, an inclosure for the stock, a dipping tank there- 130

under closed at one end and having an upwardly inclined end opening beyond the said inclosure for the escape of stock, a bottom for substantially the entire containing area 5 of the inclosure for receiving and supporting the stock, and adapted to open downward to precipitate the stock into the tank, means for at will releasing the bottom, means acting automatically for closing the bottom and 10 means for holding the bottom open against the closing action of the closing means substantially as described.

13. In a device for dipping stock, a tank for fluid, an inclosure supported thereabove, 15 a bottom of two sections hinged to the inclosure and having free adjacent edges and adapted to drop downward, members at-

tached to one of the sections of the bottom and projecting beyond the free edge thereof and upon which the opposite section is adapted to rest, pivoted devices beneath each of the section-members described for supporting the same, a manually operated lever for moving both said pivoted devices to release the sections, means simultaneously operated 20 by said lever for holding the sections downward, and means normally tending to close said sections. 25

In testimony whereof I affix my signature, in presence of two witnesses.

WILLIAM K. CRAPNELL.
